INTAKE VACUUM BREAKER

John Scheel, Dixon, Calif.

Application March 29, 1932, Serial No. 601,810

6 Claims. (Cl. 123—119)

This invention relates to internal combustion engines used in motor vehicles, my principal object being to provide a device by means of which the negative or vacuum pull on the pistons is relieved when the engine is operating on a closed throttle but the car is traveling at such a speed, with the engine in gear, as to set up a considerable vacuum drag on the pistons during their intake stroke.

10 I therefore relieve the engine of this vacuum pull when it is not wanted and which causes oil pumping and other troubles on account of the fact that insufficient air is then being drawn past the closed throttle to materially relieve the negative pressure had in the cylinders on the intake stroke of the pistons. At the same time with my device the desired compression in the cylinders which aids in the braking effect is not only retained but increased and the free influx 20 of relatively large quantities of cool air has a beneficial cooling effect on the cylinder walls.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

30 In the drawing similar characters of reference indicate corresponding parts in the several views:

Fig. 1 is a fragmentary side elevation of an intake manifold and carburetor of a gas engine partly in section and showing my vacuum breaking attachment as in operation.

Fig. 2 is a similar view showing the throttle valve open and the auxiliary air passage valve held closed.

Referring now more particularly to the characters of reference on the drawing, 1 denotes a carburetor of conventional design having an outlet passage 2 for the mixture which is connected to the adjacent and usual vertical portion 3 of the branched intake manifold proper 4. The 40 butterfly or throttle valve 5 is disposed in the passage 2 which sometimes is an integral part of the carburetor and sometimes of the intake manifold—a feature which is immaterial to this invention. The valve 5 is fixed on a turnable spindle 6 as usual to which the operating arm 7 is connected which is adapted to be manipulated from the driver's compartment of the vehicle in the conventional manner. This valve is of course arranged to be opened in one direction only from 50 its closed position.

Formed in the manifold portion 3 above the portion 2 and below the manifold proper is an auxiliary air passage 8 open at its outer end to the atmosphere. A butterfly valve 9 is disposed in this passage and is mounted on a spindle 10 60 preferably parallel to the spindle 6. The spindle 10 is preferably arranged nearer one end of the valve 9 than the other so that the vacuum pull on said valve from inside the manifold (or the corresponding air pressure from the outside) 65 will not tend to be materially counteracted by the portions of the valve above and below the spindle. The valve 9 is arranged when closed to make a tight fit in the passage and to lie at an acute angle to a vertical plane. Its direction 70 of opening movement is opposite to that of the valve 5.

An arm 11 projects radially from the spindle 10 in a substantially horizontal direction when the valve 9 is closed, and such direction is opposite to that of the opening movement of said valve, so that as the valve is opened this arm will be raised. An arm 12 projects from the spindle 6 under the arm 11; these arms being connected by a tension spring 13 having an adjusting means 14 at one end. The arms and spring are arranged so that said spring is under a slight tension when both valves are closed and the arm 12 is considerably longer than the arm 11 for a purpose which will be shortly seen. 85

By means of this arrangement it will be obvious that when the throttle valve is closed the spring 13 while holding the valve 9 closed against a low pressure offers little resistance to the opening movement of said valve by a relatively high pressure such as the vacuum pressure existing in the manifold when the throttle valve is closed and when the engine is turning over at a considerable speed, as when the car is running on its own momentum and the engine is still in gear. 90

Such pressure therefore automatically opens the valve 9 allowing a greater quantity of air to enter the manifold and cylinders than can be drawn in the same time past the closed throttle valve. The vacuum conditions in the cylinder on the intake stroke of the pistons is therefore relieved, oil pumping is eliminated, compression is improved, the cylinders are cooled, and fuel consumption is lessened. The short arm 11 allows a relatively great opening of the valve 9 to take 100 place without any great lengthening of the spring being had such as would greatly increase its tension and prevent the free opening of the valve 9 by the air pressure. When however the throttle valve is opened the movement of the long arm 12 105

accompanying such opening movement of the valve immediately expands and greatly increases the tension of the spring, so that the spring holds the valve positively closed against the action of the vacuum pressure within the manifold and thus insuring that the vehicle mixture will not be thrown out of adjustment.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In combination with the intake manifold of an internal combustion engine adapted at its outer end for connection to a carburetor, and a manually controlled throttle valve for said manifold adjacent said end; an auxiliary air intake passage connected to the manifold beyond said valve and open to the atmosphere, a valve in said passage and connections between the valves to cause the passage valve to be held closed when the throttle valve is open or closed, but allowing the passage valve to be opened to any extent by vacuum pressure within the manifold when the throttle valve is closed and without affecting the latter.

2. In combination with the intake manifold of an internal combustion engine adapted at its outer end for connection to a carburetor, and a manually controlled throttle valve for said manifold adjacent said end; an auxiliary air intake passage connected to the manifold beyond said valve and open to the atmosphere, and means associated with said valve and passage and arranged to permit air to be drawn into the man-

ifold through said passage only when the engine is operating and the throttle valve is closed.

3. In combination with the intake manifold of an internal combustion engine adapted at its outer end for connection to a carburetor, and a manually controlled throttle valve for said manifold, a means associated with said valve and manifold to permit air to be drawn into the manifold beyond the valve only when the latter is closed and the engine is operating.

4. In combination with the intake manifold of an internal combustion engine adapted at its outer end for connection to a carburetor, and a manually controlled throttle valve for said manifold having an axial and turnable spindle; an auxiliary air intake passage connected to the manifold beyond said valve and open to the atmosphere, a valve in said passage having an axial and turnable spindle, arms projecting radially from the spindles of both valves, and a tension spring connection between the arms; said arms and valves being arranged relative to each other so that the passage valve opens in a direction opposite to the opening movement of the throttle valve and when both valves are closed, the spring connection is substantially slack.

5. A structure as in claim 4, in which the arm on the passage valve spindle is relatively short, whereby an opening movement of the passage valve will not materially alter the tension of the spring connection.

6. In the intake manifold of a gas engine, a manually controlled throttle valve controlling a flow of gas mixture through the manifold, an auxiliary air passage connected to the manifold between the valve and engine, a valve in said passage, and yieldable connection means between said valves arranged so that the air valve is held closed with all positions of the throttle valve, but with a relatively small pressure when the throttle valve is closed.
